DESIGN FOR A SELF-CONTAINED HYDRAULIC PRESS

Howard F. MacMillin, Mount Gilead, Ohio, assignor, by mesne assignments, to The Hydraulic Press Corporation, Inc., Wilmington, Del., a corporation of Delaware

Application January 8, 1936, Serial No. 60,483

Term of patent 14 years

To all whom it may concern:

Be it known that I, Howard F. MacMillin, a citizen of the United States, residing at Mount Gilead, in the county of Morrow and State of Ohio, have invented a new, original, and ornamental Design for a Self-Contained Hydraulic Press, of which the following is a specification, reference being had to the accompanying drawing, forming a part thereof.

In the drawing:

I claim:

The ornamental design for a self-contained hydraulic press substantially as shown.

HOWARD F. MACMILLIN.
